RAILWAY TRACK CIRCUIT APPARATUS

Bernard E. O'Hagan, Swissvale, Pa., assignor to
The Union Switch & Signal Company, Swiss-
vale, Pa., a corporation of Pennsylvania

Application October 30, 1937, Serial No. 171,928

15 Claims. (Cl. 246—41)

My invention relates to railway track circuit apparatus, and has for an object the provision of a novel track relay arrangement having a high degree of shunting sensitivity when a train occupies the track circuit with which it is associated.

I shall describe two forms of track circuit apparatus embodying my invention, and shall then point out the novel features thereof in claims.

10 In the accompanying drawing, Fig. 1 is a diagrammatic view illustrating one form of track circuit apparatus embodying my invention. Fig. 2 is a diagrammatic view showing a modified form of the apparatus of Fig. 1, also embodying my invention.

Similar reference characters refer to similar parts in each of the two views.

Referring to Fig. 1 of the drawing, the reference characters 1 and 2 designate the track rails of a section of railway track defined by insulated rail joints 3 at each end of the section. Connected across the rails at one end of the track section is a source of current 4, here shown as a battery, which supplies current to the track circuit over a current limiting resistor 5.

The reference character R designates a track relay comprising three parallel cores 6, 7, and 8, two of which, 6 and 8, are connected at their upper ends by a backstrap 9. The remaining core 7 is spaced from the backstrap by an air gap 10. The cores 6 and 8 are provided with operating windings 11 and 12, respectively, which receive energy from the rails of the section over circuits which will be traced in detail herein-after. Accordingly, two magnetic circuits are provided, one of which includes core 6 and the other of which includes core 8, with the core 7 common to both magnetic circuits. The windings 11 and 12 are so disposed that the fluxes 35 due to these windings aid one another in the common core 7. Core 6 is equipped with a short-circuited retarding winding 13, and core 8 is equipped with a similar winding 14, but the latter winding is normally an open circuit and 40 becomes short-circuited only when the secondary relay S is released.

A tractive armature 15 is pivotally supported at bearing 16 for swinging movement toward and away from the cores 7 and 8, and a similar 45 tractive armature 17 is similarly supported for movement with respect to cores 6 and 7. The armatures 15 and 17 are biased by gravity to an open position away from the respective cores and carry contact fingers 18 and 19 which, in 50 the closed armature position shown in the draw-

ing, engage fixed contacts 20 and 21, respectively.

The secondary relay S receives operating energy from a suitable source of current having the terminals B—C, over the front contact 19—21 of relay R. Relay S controls, over its back contact 22—23, the short-circuiting of winding 14, and over its back contacts 24—25 and 26—27, the closing of the pick-up circuit for relay R. Relay S is preferably designed to have a slightly retarded pick-up so that a momentary closure of contact 19—21 will not cause relay S to pick up, thus avoiding undesired signal flashes due to opening of contact 28—29 and closing of contact 28—30, which might otherwise result during a momentary loss of shunt.

Having described the various elements of Fig. 1 comprising the apparatus embodying my invention, I shall now describe the operation of this apparatus.

When the track section is unoccupied, the apparatus will be in the condition in which it is illustrated in Fig. 1 of the drawing. That is, relay R will be maintained energized over a holding circuit which may be traced from the left-hand terminal of battery 4, limiting resistor 5, rail 2, winding 11, wire 31, resistor 32, upper portion of winding 12, wire 33, front contact 18—20, wires 34 and 35, and rail 1, to the right-hand terminal of the battery. The secondary relay S will be maintained energized over front contact 19—21 of relay R, and so the appropriate signal circuit will be closed at front contact 28—30 of this relay. The pick-up circuit for relay R and the circuit for the retarding winding 14 will both be open. The purpose served by resistor 32 included in the holding circuit is to compensate either wholly or partly, as desired, for the resistance of those turns of winding 12 which are excluded when the holding circuit is effective.

When a train enters the section, the shunt formed by the wheels and axles of the train will considerably reduce the current which traverses winding 11 and the upper portion of winding 12 in the holding circuit. Accordingly, the flux in cores 6 and 8 will rapidly decrease, but due to the presence of the short-circuited winding 13, the decrease of flux in the magnetic circuit of cores 6 and 7 will be less rapid than in the corresponding magnetic circuit of cores 8 and 7. There will, therefore, be present a magnetomotive force due to the magnetic circuit of cores 6 and 7 which will oppose the flux in the magnetic circuit of cores 8 and 7, which magnetomotive

force will drive the flux in the left-hand magnet to a lower value than would occur merely by virtue of the decrease in current of winding 12. As a result, armature 15 of the left-hand magnet will release at a higher value of train shunt resistance than it would without the opposing effect of the flux in the right-hand magnet, and will thus provide a higher degree of shunting sensitivity than is provided in the 10 usual and well-known primary-secondary relay combination. It will be apparent that winding 13 has a discriminating effect between a slow decrease in energization of relay R such as occurs when the ballast resistance decreases, and 15 a relatively rapid decrease in energization such as occurs when a train enters the section. Accordingly, winding 13 is effective in improving the shunting sensitivity of relay R by raising the release value of armature 15 and in accelerating 20 the release of this armature only under the train shunt condition, this winding being normally inactive during changes in ballast resistance.

As soon as armature 15 releases, front contact 18-20 will open and will interrupt the circuit for both windings 11 and 12, whereupon armature 17 of the right-hand magnet will quickly release. The release of armature 17 will open the circuit for relay S at contact 19-21, releasing this relay and closing 30 the retarding winding 14 as well as the pick-up circuit for relay R. The pick-up circuit may be traced from rail 2, winding 11, wire 36, back contact 26-27 of relay S, wire 37, full winding 12, wires 33 and 38, back contact 24-25 of relay S, 35 and wire 35, to rail 1. Preferably, the windings 11 and 12 will each have the same number of turns so that the right-hand and left-hand magnets may be similarly or interchangeably designed. If desired, the windings 11 and 12 may 40 be replaced by a single winding positioned on the common core 7 and supplying the necessary flux to the two magnetic circuits. By suitably tapping the single winding, a holding circuit of a decreased number of turns, similar to that 45 for the pair of windings 11 and 12 may be obtained.

The reason for equipping core 8 with a retarding winding 14 which is similar to winding 13 on core 6 is to provide similar conditions during pickup for both magnets so that at this time 50 both cores 6 and 8 will have the same number of short-circuited turns as well as the same number of operating turns. Accordingly, when 55 a train leaves the section, both armatures 15 and 17 will become attracted at about the same time, although this condition is not essential from the standpoint of operativeness. That is, winding 14 may be dispensed with, if desired, provided the apparatus is so proportioned that a 60 prior pickup of one armature 15 or 17 will not prevent the other armature from picking up. Under certain conditions, as will be explained 65 more fully in connection with Fig. 2, it may be advantageous to eliminate winding 14 in order that armature 15 will be first to pick up, thus delaying the pickup of armature 17 and introducing a corresponding delay in the pickup of relay S.

When the section becomes unoccupied, relay 70 R will pick up and the closing of contact 18-20 will reestablish the holding circuit previously traced. Also, the closing of contact 19-21 will cause relay S to pick up which will, in turn, open the pick-up circuit for relay R and the circuit 75 for winding 14, thereby restoring the sensitive

shunting condition of the apparatus, in readiness for the entry of a succeeding train into the section.

Referring to Fig. 2, the apparatus shown in this figure is essentially the same as in Fig. 1, 5 with the exception that the circuit for the secondary relay S includes a front contact 39-40 of the left-hand magnet of relay R. The advantage of this arrangement is that a quicker release of relay S will be obtained by virtue of 10 the fact that armature 15 is first to release, so that the signals will respond more quickly to the entry of a train into the section.

In this figure, the circuit for relay S may or may not be carried over the contact 19-21 of 15 the right-hand magnet, as desired. If relay S is a standard relay which does not have slow pick-up characteristics and if the retarding coil 14 is not used, then it may be desirable to include both contacts 39-40 and 19-21 in the circuit 20 for relay S, so as to time-delay the pickup of the relay. In this manner, an operation equivalent to that of Fig. 1 with an inherently slow pick-up relay S may be obtained. By using a slow pick-up relay, however, the contact 19-21 25 may be completely eliminated, the pick-up circuit for relay S being then carried over contact 39-40 alone.

A further difference between Figs. 1 and 2 is that in the latter figure the wiring for the pick-up 30 and holding circuits is slightly rearranged so as to eliminate the extra contact 24-25 of relay S. In all other respects, however, the pick-up and holding circuits for relay R are the same 35 as in Fig. 1, and will be obvious from the drawing without further explanation.

It will be apparent that the improvement in shunting sensitivity of relay R which I obtain 40 is due to two factors, namely, a higher release of armature 15 by virtue of the opposing magnetomotive force resulting from the unbalance 45 between the right-hand and left-hand magnets at the time the track is shunted, and a higher release of this armature due to the decreased ampere-turn magnetization of the relay when 50 the holding circuit is effective. However, in order to realize the advantages of my invention 55 it is not essential that the normal energizing circuit for relay R include a resistor and exclude a portion of the operating winding, or that the holding ampere-turns be decreased, so that the secondary relay S may be dispensed with entirely, if desired. That is, the full turns of both 60 windings 11 and 12 may be used not only at pickup, but also during the normal holding operation 65 of the relay. One manner in which the effect of fewer holding ampere-turns may be obtained without actually reducing the number of turns is by making the energized air gap at armature 15 greater than the energized air gap at armature 17, the two air gaps at pickup being substantially the same. Accordingly, the pick-up 70 value for armature 15 can be made the same as in the arrangement using the secondary relay S. On account of the unequal air gaps at full stroke, however, the fluxes in the right and left-hand magnets will also be unequal, the flux in the right-hand magnet being the greater of the two, so that armature 15 will have its release point substantially raised. By properly adjusting 75 this flux difference, armature 15 may be brought as close to the release point when a given shunt is applied to the track, as though a holding circuit of decreased ampere-turns were used.

Although I have herein shown and described 75

only two forms of railway track circuit apparatus embodying my invention, it is understood that various changes and modifications may be made therein within the scope of the appended claims 5 without departing from the spirit and scope of my invention.

Having thus described my invention, what I claim is:

1. In combination with a section of railway 10 track and a source of current connected across the rails of said section, a primary relay having a first and a second magnetic circuit each including a common magnetic path, means associated with said first magnetic circuit for retard- 15 ing the flux decay therein when said track section becomes shunted to thereby accelerate the flux decay in said second magnetic circuit, a secondary relay, an energizing circuit for said secondary relay including a contact of said primary relay, a 20 pick-up circuit for said primary relay connected across the rails of said section and including a contact of said secondary relay as well as the full operating winding of said primary relay, and a holding circuit for said primary relay controlled 25 by a contact governed by said second magnetic circuit and including only a portion of the operating winding of said primary relay.
2. In combination with a section of railway 30 track and a source of current connected across the rails of said section, a primary relay having a first and a second magnetic circuit each including a common magnetic path, means associated with said first magnetic circuit for retarding the flux decay therein when said track section becomes 35 shunted to thereby accelerate the flux decay in said second magnetic circuit, a secondary relay, an energizing circuit for said secondary relay including a contact of said primary relay, a pick-up circuit for said primary relay connected across 40 the rails of said section and including a contact of said secondary relay as well as the full operating winding of said primary relay, a resistor, and a holding circuit for said primary relay controlled by a contact governed by said second magnetic 45 circuit and including only a portion of the operating winding of said primary relay and said resistor.
3. A track relay for improving the shunting sensitivity of a track circuit comprising, in combination, two magnetic circuits for said track relay each including a common magnetic path and each adapted to be energized from the track, a control armature for said track relay associated with one of said magnetic circuits, and means 50 associated with the other of said magnetic circuits and discriminating between a relatively slow decrease in energization of the track relay such as occurs due to a decrease in ballast resistance and a relatively rapid decrease in energization 55 of the track relay such as occurs due to a train shunt for accelerating the release of said armature when said track relay becomes shunted.
4. A track relay for improving the shunting sensitivity of a track circuit comprising, in combination, two magnetic circuits for said track relay each including a common magnetic path and each adapted to be energized from the track, a control armature for said track relay associated with one of said magnetic circuits, and means 60 associated with the other of said magnetic circuits for retarding the flux decay therein when the track becomes shunted to thereby accelerate the flux decay in said one magnetic circuit and so to accelerate the release of said armature.
5. A track relay for improving the shunting 65 sensitivity of a track circuit comprising, in combination, two magnetic circuits for said track relay each including a common magnetic path and each adapted to be energized from the track, a control armature for said track relay associated with one of said magnetic circuits, a short-circuited winding associated with the other of said magnetic circuits for retarding the flux decay 70 therein when the track becomes shunted to thereby accelerate the flux decay in said one magnetic circuit and so to accelerate the release of said armature.
6. A track relay for improving the shunting 75 sensitivity of a track circuit comprising in combination, a first and a second magnetic circuit for said track relay each including a common magnetic path and each adapted to be energized from the track, a first and second armature associated respectively with said first and second magnetic circuits, means associated with said first magnetic circuit for retarding the flux decay therein when the track becomes shunted to accelerate the flux decay in said second magnetic circuit and so to release said second armature before said first armature releases, and signaling apparatus controlled by said two armatures.
7. In combination with a section of railway 30 track and a source of current connected across the rails of said section, a track relay having two magnetic circuits each including a common magnetic path, a circuit including the rails of said section for energizing said two magnetic circuits, an armature associated with each of said magnetic circuits, and means associated with one of said magnetic circuits effective when the 35 track section becomes shunted by a train for accelerating the release of the armature associated with the other of said magnetic circuits.
8. In combination with a section of railway 40 track and a source of current connected across the rails of said section, a track relay having two magnetic circuits each including a common magnetic path, a circuit including the rails of said section for energizing said two magnetic circuits, an armature associated with one of said magnetic 45 circuits, and means associated with the other of said magnetic circuits effective when said track section becomes shunted by a train for accelerating the release of said armature.
9. In combination with a section of railway 50 track and a source of current connected across the rails of said section, a track relay having two magnetic circuits each including a common magnetic path, a circuit including the rails of said section for energizing said two magnetic circuits, 55 an armature associated with one of said magnetic circuits, and a short-circuited winding associated with the other of said magnetic circuits effective when said track section becomes shunted by a train for retarding the flux decay in said other magnetic circuit so as to accelerate the flux decay in said one magnetic circuit and expedite the release of said armature.
10. In combination with a section of railway 65 track and a source of current connected across the rails of said section, a track relay having two magnetic circuits each including a common magnetic path, a circuit including the rails of said section for energizing said two magnetic circuits, 70 an armature associated with one of said magnetic circuits, means associated with the other of said magnetic circuits effective when said track section becomes shunted by a train for accelerating the release of said armature, and means con- 75

trolled by said armature for improving the shunting sensitivity of said track relay.

11. In combination with a section of railway track and a source of current connected across the rails of said section, a track relay having two magnetic circuits each including a common magnetic path, a circuit including the rails of said section for energizing said two magnetic circuits, an armature associated with each of said magnetic circuits, means associated with one of said magnetic circuits effective when the track section becomes shunted by a train for accelerating the release of the armature associated with the other of said magnetic circuits, and means controlled by both said armatures for improving the shunting sensitivity of said track relay.

12. In combination with a section of railway track and a source of current connected across the rails of said section, a track relay having a first and a second magnetic circuit each including a common magnetic path, a circuit including the rails of said section for energizing said first and said second magnetic circuits, a first and a second armature associated respectively with said first and said second magnetic circuits, means associated with said second magnetic circuit for accelerating the release of said first armature upon shunting of said track section, an auxiliary relay controlled by said first armature, and means controlled by said auxiliary relay and effective when the shunt is removed from said track section for equalizing the pick-up time for said first and second armatures.

13. In combination with a section of railway track and a source of current connected across the rails of said section, a track relay having two magnetic circuits each including a common mag-

netic path, means receiving energy from the rails of said section for setting up aiding fluxes in said two magnetic circuits, an armature associated with one of said magnetic circuits, and means associated with the other of said magnetic circuits effective upon a rapid decrease of the energy received from said rails when a train enters said section for aiding the release of said armature.

14. A track relay for railway signaling track circuits comprising, in combination, two magnetic circuits for said track relay each including a common magnetic path, means for setting up aiding fluxes in said two magnetic circuits, and means associated with one of said magnetic circuits effective upon a relatively rapid decrease of flux therein for accelerating the decrease of flux in the other of said magnetic circuits to thereby improve the shunting sensitivity of said track relay.

15. In combination with a section of railway track and a source of current connected across the rails of said section, a track relay having two magnetic circuits each including a common magnetic path, means receiving energy from the rails of said section for setting up aiding fluxes in said two magnetic circuits, an armature associated with one of said magnetic circuits, and means associated with the other of said magnetic circuits and discriminating between a rapid decrease in the energy received from said rails such as occurs when a train enters the section and a slow decrease in said energy due to a decrease in ballast resistance for modifying the release value of said armature.

BERNARD E. O'HAGAN.
